UNITED STATES PATENT OFFICE.

WARD S. IRELAND, OF ST. LOUIS, MISSOURI, AND WALTER E. LIPPERT, OF CINCINNATI, OHIO, ASSIGNEES, BY DIRECT AND MESNE ASSIGNMENTS, TO NATIONAL SHORT-HAND MACHINE COMPANY, OF ST. LOUIS, MISSOURI, A CORPORATION OF DELAWARE.

TYPE-WRITING MACHINE.

1,316,839.

Specification of Letters Patent. Patented Sept. 23, 1919.

Application filed November 18, 1916. Serial No. 132,065.

To all whom it may concern:

Be it known that we, WARD S. IRELAND and WALTER E. LIPPERT, citizens of the United States of America, residents, respectively, of the city of St. Louis, State of Missouri, and of Cincinnati, in the county of Hamilton, State of Ohio, have invented certain new and useful Improvements in Type-Writing Machines, of which the following is a full, clear, and exact description, reference being had to the accompanying drawings, forming a part of this specification.

This invention relates to improvements in typewriting machines, and more particularly to paper feeding mechanism adapted for use in shorthand machines.

One of the objects of the invention is to produce a strong, simple and accurate paper feeding device adapted to coöperate with the finger keys of a shorthand machine, and adapted to yield to prevent the paper from being torn when it is gripped between the printing elements, or otherwise restrained, during the operation of the paper feeding device. With this object in view the preferred form of the invention comprises printing elements adapted to grip the paper, a universal bar movable in synchronism with said printing elements, and a yieldable paper feeding device operable by the universal bar. The universal bar is, preferably, free to move after the paper has been gripped by the printing elements, and the paper feeding device, which partakes of the movements of the universal bar, includes a transmission member which yields after the paper has been restrained by the printing elements, thus preventing the paper feeding device from tearing or otherwise injuring the paper.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a longitudinal section of a shorthand machine embodying the features of this invention.

Fig. II is a detail view showing the roll of paper and the friction elements associated therewith.

Fig. III is an enlarged side elevation illustrating the universal bar and the paper feeding device.

Fig. IV is a fragmentary section taken approximately on the line IV—IV, Fig. III.

Fig. V is a detail view of the ratchet wheel which forms part of the paper feeding device.

Fig. VI is a detail view of the paper feeding wheel associated with the ratchet wheel.

To illustrate the preferred form of the invention, we have shown a short hand machine provided with a housing 1, a type holder 2 arranged in said housing (Fig. I), a type bar 3 in said type holder, and an inking ribbon 4 adjacent to the line of type on the type bar 3. The paper passes from a supply roll A, over a roller 5 under and partially around a roller 5', in front of and over an uncurling device 6, and then to a paper feeding device whereby it is unwound from the roll and fed through an opening 7 at the rear of the machine.

The key actuating devices preferably include a series of angular levers each having an upwardly extending arm 8 at its front end and a character key 9 at the upper end of said arm. Any suitable shorthand code may be used and if desired the keys may be provided with characters corresponding to the line of type characters on the type bar 3 as is well understood in this art. Each key lever includes an arm 10 extending rearwardly from its arm 8, an arm 11 extending upwardly from the rear portion of said arm 10. The series of key levers is pivotally supported by a pivot member 12 located at the junctions of the lever arms 10 and 11. The upper end of each lever arm 11 is provided with a forwardly extending printing hammer 13 which lies adjacent to the type 3 as shown in Fig. I. Restoring springs 14 tend to retain the key levers in an engagement with abutment 15.

When one of the finger keys 9 is depressed, the key lever associated therewith turns about the axis of the pivot member 12 and a printing hammer moves toward the type 3, thereby forcing the paper and inking ribbon toward the type and printing one of the type characters on the paper. The key

levers may be operated independently of each other, or any desired number of key levers may be operated simultaneously.

The universal bar associated with the key

5 levers includes a transverse abutment holder 18 (Figs. I, III and IV) arranged in front of the lever arms 11 and provided with a suitable abutment 19 which engages all of said lever arms. The universal bar also includes a pair of arms 20 and 20' pivotally supported by the pivot member 12 and secured near their upper ends to the transverse abutment holder 18. 22 designates a connecting member uniting the arms 20 and 15 20' of the universal bar, said connecting bar being located at the rear of the lever arms 11. 23 designates a restoring spring (Fig. I) tending to retain the universal bar in the position shown in the drawing. The 20 transverse abutment 19, forming part of the universal bar structure is so arranged that the universal bar will move in response to movements of any one of the key levers.

The paper feeding device preferably comprises a rotatable shaft 24, a pair of feed wheels 25 and 25' fixed to said shaft, a ratchet wheel 26 loosely fitted to the shaft, and a pawl carrier 27 loosely fitted to said shaft. 28 designates a pawl (Fig. III) pivoted to the pawl carrier 27, and 29 designates a spring connecting said pawl to the pawl carrier. The spring 29 tends to force the pawl into engagement with the ratchet wheel 26, as shown by dotted lines in Fig. 35 III. The arm 20 of the universal bar is provided with an extension 30 (Figs. III and IV) which co-operates with an arm 31 on the pawl carrier 27. A spring 32, secured to the universal bar, forces the arm 31 into engagement with the universal bar extension 30, said arm 31, being provided with a pad which bears against said extension, as seen in Fig. III. The arm 31, extending from the pawl carrier, is so arranged between the 45 spring 32 and universal bar extension that the pawl carrier will partake of the movements of the universal bar. It will now be understood that the pawl carrier 27 as well as the universal bar, is under the control of the key levers, and that the pawl carrier is adapted to oscillate in response to movements of said key levers.

The strip of paper is preferably perforated, as shown in Fig. II, to receive the 55 teeth which project from the feed wheels 25 and 25'. The feed wheel 25 is recessed (Figs. IV, V and VI) to receive a boss 34 and pins 35 which extend from one side of the ratchet wheel 26. 36 designates compression springs located in the recesses 37, each of said springs being located between a pin 35 and a wall of one of the recesses. Under normal conditions the springs 36 transmit movement from the ratchet wheel 65 26 to the feed wheel 25 and shaft 24; how-

ever, when the paper is caught by the printing elements, or restrained in any other manner, the springs 36 will yield to prevent the paper from being torn by the paper feeding device.

When a key is depressed, or when several keys are depressed simultaneously, the universal bar moves forwardly about the axis of the pivot member 12 and the pawl carrier 27 turns about the axis 70 of shaft 24 so as to advance the ratchet wheel 26 one step, thereby turning the feed wheels 25 and 25' to unwind the paper and advance it one step. At the end of the paper feeding operation, the printing hammer or 80 hammers 13 force the paper and inking ribbon toward the type and print the selected character or characters. After the paper and inking ribbon have been gripped between the type and hammers the latter will 85 move a slight distance to insure the desired printing action. During this final movement the universal bar continues to move with the lever arms 11 and the pawl carrier 27 and ratchet wheel 26 move with the 90 universal bar. At this time the ratchet wheel moves independently of the paper feeding wheels, the springs 36 being compressed in the recesses 37.

The type bar 3 is preferably yieldingly 95 supported in the type holder 2, a piece of rubber 40 or other yielding material being interposed between the type bar and a wall of the type holder. The type is therefore free to adjust itself to the type hammers during 100 the printing operations, and although the type hammers and universal bar move an appreciable distance while the paper is held by the printing elements, this additional movement is not transmitted to the paper 105 feeding wheels, the springs 36 being adapted to compensate for such movement as previously described.

41 designates a yieldable stop (Fig. I) adapted to be engaged by the member 18 of 110 the universal bar during the printing operations. This yielding stop prevents the universal bar from being thrown away from the lever arms 11 during the key operations, and it does not materially retard the movement of said lever arms during the printing operations when the type bar is forced 115 backwardly into the type holder.

The inner end of the strip of paper is firmly secured to a core 42 (Figs. I and II) 120 provided at its ends with friction members 43 and 44 which turn with the roll of paper. A friction member 45, engaging the friction member 43, is rigidly secured to a stationary arm 46. 47 designates a yieldable friction 125 member slidably fitted to a spring pocket at the lower end of a stationary arm 48. A spring 49 forces the friction member 47 into engagement with the friction member 44, at the same time forcing the friction mem- 130

ber 43 into engagement with the stationary friction member 45. The spring-pressed friction elements tend to prevent the roll of paper from turning, and upon the operation 5 of the paper feeding device the paper is pulled along the uncurling device 6 (Fig. I), said uncurling device being a small rod fixed to stationary parts of the machine. In passing over to the uncurling device, the 10 strip of paper is turned abruptly in a direction opposed to the direction in which it was wound on the roll. By holding the paper under tension and pulling it over the uncurling device in the manner illustrated, 15 the paper is uncurled and fed from the machine in an absolutely straight condition. At the end of each printing operation, when the type bar 3 is forced backwardly 20 in the type holder, the strip of paper will be pulled a slight distance without tearing, such movement being permitted by the yielding devices which support the roll of paper.

A retaining pawl 50 (Fig. I) is fitted to a 25 ratchet wheel 51 to prevent retrograde movement of the paper feeding wheels, said ratchet wheel being secured to the shaft 24.

The printing elements herein shown are 30 claimed in an application for patent filed by Ward S. Ireland on Nov. 18, 1916, Serial No. 132,076. The key lever guide is claimed in an application filed by Ward S. Ireland and W. E. Lippert on Nov. 18, 1916, Serial No. 132,077. The universal bar is claimed 35 in an application filed by W. S. Ireland and W. E. Lippert on Nov. 18, 1916, Serial No. 132,078. The paper straightener is claimed in an application filed by W. S. Ireland on May 19, 1917, Serial No. 169,620. Reference 40 is also made to an application filed by W. S. Ireland and W. E. Lippert on Nov. 18, 1916, Serial No. 132,066, wherein we have shown and claimed some of the details of construction of the paper feeding device.

45 We claim:

1. In a feeding device for typewriting machines, the combination of a universal bar, a rotary drive member operable by said universal bar, a rotary driven member, and a 50 yieldable device for transmitting movement from said rotary drive member to said rotary driven member.

2. In a feeding device for typewriting machines, the combination of a universal bar, a 55 rotary drive member operable by said universal bar, a rotary driven member, and a yieldable device for transmitting movement from said rotary drive member to said rotary driven member, said yieldable device 60 being movable in a circular path with said members.

3. In a typewriting machine adapted to receive a strip of paper, printing elements adapted to grip the paper, a universal bar 65 movable in synchronism with said printing

elements, and a paper feeding device including a rotary drive member operable by said universal bar, a rotary driven member, and a yieldable device for transmitting movement from said rotary drive member to said 70 rotary driven member.

4. In a typewriting machine adapted to receive a strip of paper, printing elements adapted to grip the paper, a universal bar movable in synchronism with said printing 75 elements, and a paper feeding device including a rotary drive member operable by said universal bar, a rotary driven member, and a yieldable device for transmitting movement from said rotary drive member to said 80 rotary driven member, said yieldable device being movable in a circular path with said members.

5. In a typewriting machine adapted to receive a strip of paper, printing elements 85 adapted to grip the paper, a universal bar movable in synchronism with said printing elements, and a paper feeding device including a drive member operable by said universal bar, a driven member movable about 90 the axis of said drive member, and a yieldable device for transmitting movement from said drive member to said driven member.

6. In a typewriting machine adapted to receive a strip of paper, printing elements 95 adapted to grip the paper, a universal bar movable in synchronism with said printing elements, and a paper feeding device including a drive wheel movable step by step in response to movement of said universal bar, 100 a driven wheel, and a yieldable device for transmitting movement from said drive wheel to said driven wheel.

7. In a typewriting machine adapted to receive a strip of paper, printing elements 105 adapted to grip the paper, a universal bar movable in synchronism with said printing elements, and a paper feeding device including a drive wheel operable by said universal bar, paper feeding wheels adapted to engage 110 the paper and a yieldable device for transmitting movement from said drive wheel to said driven wheel.

8. In a typewriting machine adapted to receive a strip of paper, printing elements 115 adapted to grip the paper, a universal bar movable in synchronism with said printing elements, and a paper feeding device including a rotary drive member operable by said universal bar, a rotary driven member, and a yieldable device for transmitting movement from said rotary drive member to said 120 rotary driven member, said yieldable device being located between the adjacent side faces of said drive and driven members.

9. In a typewriting machine adapted to receive a strip of paper, printing elements adapted to grip the paper, a universal bar movable in synchronism with said printing 125 elements and a paper feeding device includ-

ing a ratchet wheel operable by said universal bar, a paper feeding wheel, and a spring for transmitting movement from said ratchet wheel to said paper feeding wheel.

- 5 10. In a typewriting machine adapted to receive a strip of paper, printing elements adapted to grip the paper, a universal bar movable in synchronism with said printing elements, and a paper feeding device including a drive wheel operable by said universal bar, a driven wheel, one of said wheels being provided with a recess and the other being provided with a projection which extends into said recess, and a yieldable device arranged between said projection and a wall of said recess so as to transmit move-

ment from said drive wheel to said driven wheel.

11. In a typewriting machine adapted to receive a strip of paper, printing elements adapted to grip the paper, a universal bar movable in synchronism with said printing elements, and a paper feeding device including a rotatable shaft, a pair of paper feeding wheels fixed to said shaft, a drive member loosely fitted to said shaft, said drive member being operable by said universal bar, and a yieldable device for transmitting movement from said drive member to said shaft. 20 25

WARD S. IRELAND.
WALTER E. LIPPERT.
